UNITED STATES PATENT OFFICE

135,768

DESIGN FOR A FLASH OR SIGNAL LIGHT

Raymond L. Falge, Bethesda, Md., assignor to
Falge Engineering Service, Bethesda, Md.

Application March 22, 1943, Serial No. 109,796

Term of patent 14 years

To all whom it may concern:

Be it known that I, Raymond L. Falge, a citizen of the United States, residing in Bethesda, Montgomery County, Maryland, have invented a new, original, and ornamental Design for a Flash or Signal Light, of which the following is a specification, reference being had therein to the accompanying drawing, forming a part thereof.

In the drawing:

Fig. 1 is a side view, and

Fig. 2 is a front end view of a flash or signal light showing my new design.

I claim:

The ornamental design for a flash or signal light, as shown.

RAYMOND L. FALGE.
